United States Patent Office

Des. 216,149
Patented Nov. 25, 1969

216,149

EARRING

Bernard D. Shapiro, 74 Tars Drive, Nassau County,
Roslyn, N.Y. 11576

Filed June 28, 1968, Ser. No. 12,549

Term of patent 14 years

Int. Cl. D11—01

U.S. Cl. D45—9

FIG. 1

FIG. 2

FIG. 3

I claim:

The ornamental design for an earring, as shown and described.
